UNITED STATES PATENT OFFICE.

JOSHUA E. RYON, OF DESDEMONA, TEXAS.

PERMUTATION-PADLOCK.

1,222,145.

Specification of Letters Patent. Patented Apr. 10, 1917.

Application filed January 29, 1915. Serial No. 5,101.

To all whom it may concern:

Be it known that I, JOSHUA E. RYON, a citizen of the United States, residing at Desdemona, in the county of Eastland and State of Texas, have invented certain new and useful Improvements in Permutation-Padlocks, of which the following is a specification.

My invention relates to padlocks and more particularly to permutation padlocks.

The primary object of my invention resides in the provision of a padlock of the character described wherein is provided a keyless locking means which can be opened only by a certain combination or arrangement of the operating means, thereby preventing the surreptitious opening of the lock by unauthorized persons.

Another object of my invention resides in the provision of a lock casing having a shackle pivotally associated therewith, the latter being engageable by novel retaining means positioned within the casing for removably holding the shackle in engagement with the casing.

A further object of my invention resides in the provision of a novel actuating means mounted in the casing and associated with the retaining means for facilitating the actuation of the retaining means for releasing the shackle from the casing.

A still further object of my invention resides in the provision of a novel means for mounting the actuating means, the latter being peculiarly arranged so as to necessitate a registration of the parts preparatory to the actuation of these parts as a whole for releasing the retaining means.

A still further object of my invention resides in the provision of a novelly constructed resilient means that is associated with the retaining means on the shackle for facilitating the removal of the retaining means from the shackle when the lock has been operated and for automatically causing the shackle to assume an open position when released.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection

with the accompanying drawings and pointed out in the claims forming a part of this specification.

In the drawings:—

Fig. 1 is a side elevational view of my invention showing to advantage the positioning of the actuating disks; 60

Fig. 2 is a side elevational view of the same with the cover removed showing the shackle in a closed position; 65

Fig. 3 is a longitudinal sectional view of my invention through the casing looking toward the cover showing the shackle in an open position, the parts being so arranged 70 that this may be made possible;

Fig. 4 is a vertical sectional view taken on the line 4—4 of Fig. 2 and looking in the direction in which the arrow points; and

Fig. 5 is an enlarged fragmentary sec- 75 tional view of the actuating mechanism.

Referring more particularly to the drawings in which similar reference numerals designate like or corresponding parts throughout the different views, I provide a 80 casing 1, formed preferably of metal and provided adjacent the upper end thereof with openings 2 and 3, the openings receiving the ends of the substantially U-shaped shackle 4. One end of the shackle 4 is pivot- 85 ally mounted within the casing by means of a pin 5, the extreme free end of the connecting end of the shackle being slightly enlarged and provided on its extreme under surface with a recess 6 and further provided 90 adjacent the respective sides of the recess 6 with laterally extending lugs 7, both the recess and the lugs being for a purpose to be hereinafter described. The opposite end of the shackle 4 is provided with a recess 8, the 95 latter forming a head 9 on the terminal thereof, which head 9 is normally arranged in removable engagement with a complementary recess 10 of a tumbler 11. A head 12 is formed on the tumbler when the recess is 100 provided, the head being complementary to the recess 8 in the shackle 4 and both the recesses 8 and 10 and the heads 9 and 12 res- 105 pectively in the shackle and tumbler constitute a suitable catch for facilitating the removable engagement of the parts when desired. The tumbler 11 has its inner end curved as at 13 and the extreme free inner end reduced to provide a shoulder which latter has bearing thereagainst the reduced 110 end of a substantially arcuate lever 15. Likewise the reduced end of the tumbler

bears against the shoulder provided by reducing the lever 15 and these parts are held in rigid relation with respect to each other by a suitable fastening device 14 the latter by a suitable fastening device 14 the latter 5 being pivotally mounted in the casing at a point substantially intermediate its ends, by means of a pin 16. A projection 17 is formed on the arcuate lever 15 at a point adjacent the pivot point and extends laterally from the lever for a purpose to be hereinafter described.

In order to automatically force the shackle into an open position when the retaining means or tumbler has been removed from engagement therewith in a manner to be hereinafter described, I have provided a suitable elastic element preferably a leaf spring 18, the latter being bent upon itself to a point adjacent one end thereof into a circular configuration as shown at 19, the circular portion being disposed about a suitable pin 20 mounted in the casing. The arms of the spring are disposed at substantially right angles to each other, the entire spring assuming a substantially L-shaped form, the longer arm of the spring extending across the casing and in engagement with the lugs 7 and the recess 6 on the inner end of the shackle, and the opposite or short arm of the spring is engaged on the free end of the arcuate lever 15. By this arrangement it can be seen that the longer of the arms exerts a pressure which normally tends to force the shackle upwardly from the casing, 35 whereas the short arm exerts downward pressure on the arcuate lever and due to the fact that the same is in rigid engagement with the tumbler, the tumbler is normally held in yielding engagement with the free 40 end of the shackle 4 as clearly shown to advantage in Fig. 2 of the accompanying drawings. It will be understood that the curved end of the tumbler 13 and the arcuate lever 15 are arranged in closely spaced relation 45 with the outer edge of the casing, thus providing a suitable space in approximately the center of the casing for a purpose to be hereinafter described.

Secured to the casing by means of the 50 pins 5, 16 and 20 is a cover 21, the latter being of a substantially circular configuration and having the upper edges thereof arranged in alignment with the outer edges of the casing. The cover is provided with a 55 circular screw-threaded opening 22 in which is removably received my improved operating means for releasing the retaining means from engagement with the shackle.

The improved operating means in this instance consists essentially of a substantially circular plate 23, the outer periphery of which is arranged in screw-threaded engagement with the opening 22, the plate being provided with a centrally positioned opening 65 in which is rotatably mounted a tubular

shaft 24, on the outer end of which is rigidly mounted an actuating disk 25 having a pointer 26 projecting from one point of the periphery for a purpose to be hereinafter referred to. A supporting disk 27 is rigidly mounted on the inner end of the tubular shaft 24 and is positioned within the space provided in the casing by the peculiar arrangement of the tumbler and arcuate lever. In order to hold the disk 27 in its proper 75 position and in spaced relation with the plate 23, I have disposed a collar 28 about the tubular shaft and the latter also constituting a bearing for supporting the disk thereon. A stub shaft 29 is rotatably mounted in the supporting disk 27 at a point to one side of the center of the disk, the said stub shaft receiving a gear 30, the latter being arranged in abutting relation with the disk and in rigid connection with the shaft 80 For the purpose of engaging the projection 17 carried by the arcuate lever for releasing the shackle from engagement with the tumbler in a manner to be hereinafter described, I have rigidly and eccentrically mounted a 90 disk 31 on the free end of the stub shaft 29, the disk being so arranged as to project beyond the periphery of the supporting disk 27 when desired so that the same may engage the projection 17. In order to rotate 95 the gear 30 and consequently rotate the eccentrically mounted disk 31, I have journaled another stub shaft 32 in the tubular shaft 24 and rigidly mounted on the inner end of the shaft 32 a gear 33, similar in construction with the gear 30. The gear 33 is arranged in abutting relation with the supporting disk 27 and has the teeth thereof in mesh with the teeth of the gear 30 so that when the shaft 32 is rotated, a rotary movement is consequently imparted to the eccentrically mounted disk 31 through the medium of the gear 30. The outer end of the shaft 32 projects slightly beyond the outer edge of the tubular shaft 24 and receives a 100 collar 34 which is loosely disposed thereabout and constitutes a suitable bearing for the actuating disk 35 rigidly secured to the extreme terminal of the shaft 32 and which disk 35 has its outer periphery roughened to 105 facilitate the rotation of the same. A pointer 36 projects from the under surface of the disk 35 slightly beyond the periphery thereof and when the same is in a desired position constitutes a suitable means for determining when the parts positioned within the casing are so arranged as to actuate the retaining means in the casing.

The outer surface of the cover 17 is provided with suitable graduations, the same 115 being positioned about the actuating disks 25 and 35.

The operation of my invention is as follows:

Assuming that the lock is in a position as 120

shown in Fig. 2 and it is desired to open the same, all that is necessary to do is to rotate the actuating disk 25 until the pointer 26, which is arranged in substantial alignment with the eccentrically mounted disk, points in a direction toward the extreme lower end of the casing or so that the eccentrically mounted disk 31 will be positioned directly above the projection 17 on the arcuate lever, thereupon the actuating disk 35 is rotated until the pointer 36 thereon assumes a position of registration with the pointer 26. During the rotation of this part the gear 33 which is carried by the shaft 32 is also rotated and imparting the rotary motion to the gear 30 and consequently to the eccentrically mounted disk 31 and because of its eccentric mounting and the fact that when rotated it projects beyond the periphery of the supporting disk 27 it will engage the projection 17 on the arcuate lever and force the arcuate lever downwardly against the tension of the spring 18 simultaneously causing the tumbler 11, which is in pivotal connection with the arcuate lever, to be drawn inwardly from engagement with the free end of the shackle 4. Because of the arrangement of the spring with the shackle when the free end of the shackle is released the spring will automatically force the free end of the shackle upwardly from the casing, thus opening the lock. In closing the lock all that is necessary to do is to rotate the actuating disk 35 until the eccentrically mounted disk 31 is in removable engagement with the projection 17 whereupon the shackle will be forced downwardly into engagement with the tumbler 11.

Although I have shown and described the preferred embodiment of my invention, I desire it to be understood that I am not to be limited to the exact details shown, however, great stress is laid upon the arrangement of the peculiar construction and arrangement of the operating mechanism that is associated with the retaining means for releasing the shackle.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention,

what I claim as new and desire to secure by Letters Patent, is:—

1. A padlock including a casing, a shackle having one end pivotally mounted within the casing, an arcuate lever pivotally mounted within the casing, a projection formed on said lever, a tumbler rigidly mounted on one end of said arcuate lever for removable engagement with the free end of the shackle for holding the shackle in engagement with the casing, a spring having its respective ends in engagement with the connected end of said shackle and the free end of said arcuate lever for holding said tumbler in engagement with the shackle before actuation and for facilitating the outward movement of the shackle after actuation, and actuating means rotatably mounted within the casing for engagement with said projection for removing said tumbler from engagement with said shackle. 70 75 80 85

2. A padlock including a casing, a shackle having one end pivotally mounted within the casing, an arcuate lever pivotally mounted within the casing, a projection formed on said arcuate lever, a tumbler rigidly mounted on one end of said arcuate lever for removable engagement with the free end of the shackle, a spring having the respective ends in engagement with the free end of said 90 95 100 105 arcuate lever and the connected end of the shackle for holding the tumbler in engagement with the shackle before actuation and for facilitating the outward movement of the shackle from the casing when actuated, a disk rotatably mounted within the casing and positioned adjacent said arcuate lever, a smaller disk eccentrically mounted adjacent the periphery of said larger disk, means for rotating said larger disk for setting said eccentrically mounted disk, and means for rotating said eccentrically mounted disk for moving the same into engagement with said projection for moving said tumbler from engagement with said shackle. 110

3. A padlock including a casing, a shackle having one end pivotally mounted within the casing, retaining means movably mounted within the casing for removable engagement with the shackle, a supporting disk rotatably mounted within the casing, a small disk eccentrically mounted upon the supporting disk, and means for rotating the eccentrically mounted disk for moving the same into engagement with the retaining means for 115 120 125 releasing the shackle from the casing.

4. A padlock including a casing, a shackle having one end pivotally mounted therein, an arcuate lever pivotally mounted within the casing, a projection extending laterally from the arcuate lever, a tumbler rigidly connected to one end of said arcuate lever for engagement with the free end of the shackle for removably holding the same in engagement with the casing, resilient means 130

within the casing for engagement with the free end of the arcuate lever and the connected end of the shackle for holding the tumbler in engagement with the shackle before actuation and for facilitating the outward movement of the shackle from the casing after actuation, a tubular shaft rotatably mounted in the casing, a supporting disk rigidly mounted on the inner end thereof, 10 another disk eccentrically mounted adjacent the periphery of the supporting disk, an actuating disk on the outer end of the tubular shaft for facilitating the rotation of the supporting disk for setting the eccentrically mounted disk, a stub shaft journaled within said tubular shaft, means on the inner end 15 of the stub shaft for imparting a rotary

motion to the eccentrically mounted disk, an actuating disk rigidly mounted on the outer end of the stub shaft for imparting a 20 rotary motion thereto and consequently moving said eccentrically mounted disk into engagement with said projection for removing said tumbler from said shackle, and pointers extending from the peripheries of said actuating disks for facilitating the setting and actuation of the disks. 25

In testimony whereof I affix my signature in presence of two witnesses.

JOSHUA E. RYON.
